UNITED STATES PATENT OFFICE

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY

BACK GAUGE MECHANISM FOR SHOE SEWING MACHINES

Application filed February 14, 1929. Serial No. 339,883.

The present invention relates to sewing machines of the type employed to sew together the upper and the sole of a turn shoe, or the upper, insole and welt of a welt-shoe. It has especial reference to the means employed for moving the back gauge, or the combined back gauge and welt guide in common use, into contact with the shoe and locking it in such relation while the needle is being retracted, and for moving it away from the shoe subsequently to permit the latter's feeding movement.

In the forms of back gauge actuating mechanism which have entered into common use the parts have been heavily constructed and rigidly combined. Variations in the thickness of the work at various points in the shoe have brought about the adoption of spring means for bringing the back gauge forward into contact with the shoe, with the result that through strengthening the spring in order to actuate the back gauge with sufficient rapidity, the back gauge has been made to pound or hammer against the shoe during the sewing operation to an extent making it difficult for the operator to hold the shoe in proper position.

The principal object of the invention is to provide an improved back gauge mechanism which will act without causing this objectionable pounding against the shoe.

To this end, the invention comprises a back gauge mechanism of a design permitting the use of lightly constructed parts and arranged to swing the back gauge in an arc so as to reduce the force of the blow against the shoe, with the locking and retracting mechanism entirely disconnected from the back gauge while the latter advances, to prevent their contributing to the inertia of the parts.

Another object of the invention is to cause the back gauge to follow the path of the needle, so that the back gauge will encounter the shoe in the same relation to the needle regardless of variations in the thickness of the work and also so that the blow of the back gauge will merge with the impact of the needle upon the work without disturbing the shoe in the hands of the operator.

To this end, the back gauge is operably

combined with a guideway serving to make the engaging end of the back gauge perform as if turning about the center of swing of the needle.

Another object of the invention is to provide a back gauge organization in which there will be no breakage of parts such as has resulted from wear of the cams and the parts actuated by them, with consequent overlapping of the necessarily close timing of their actions causing the back gauge retracting devices to act while the back gauge has still remained fixed by its locking devices.

With this end in view, the force applied to retract the back gauge is delivered through yielding means so that if the retraction should be attempted before the locking means has released the back gauge, the moving of the back gauge will be postponed until such release without harmful strain on the parts.

The present invention also consists in the devices, combinations, and arrangements of parts hereinafter described and claimed, the advantages of which will be obvious to those skilled in the art from the following description.

The several features of the present invention will be clearly understood from an inspection of the accompanying drawings, in which:

Fig. 1 is a view in side elevation of a turn-shoe inseam sewing machine embodying said features in their preferred forms; Fig. 2 is a side view of certain parts shown in Fig. 1 on a larger scale, illustrating the relation of the shoe, the needle, the back gauge and its actuating and locking mechanism while being retracted from the shoe; Fig. 3 is a view similar to Fig. 2, showing the relation of the said parts just prior to the advance of the back gauge toward the shoe; Fig. 4 is a view similar to Fig. 2 showing the relation of the parts when the back gauge is locked against the shoe.

Having reference to the drawings: The machine illustrated herewith is provided with a curved hooked needle, a needle guide, a looper, a thread arm, a channel guide, a back rest, a back rest slide, and a tension device, all having the same general ar-

angement and mode of operation, except as hereinafter described, as the corresponding parts of the welt and turn machine disclosed in Patent No. 1,108,560 granted August 25, 1914 to A. Eppler for Shoe sewing machine. Reference may be had to said patent for a full and complete description of the parts not described herein.

The needle 2 is mounted in the usual manner on the needle segment 4, swinging about a center formed by the pivot 6 fixed in the frame of the machine and actuated in the usual manner, the said needle segment 4 being supported in its movement by a web 8 fixed 10 to the framework of the machine. The back gauge 10 has its engaging end of forked design permitting the latter to bear against the shoe at either side of the needle which passes between the prongs thereof. It is pivotally supported at 12 with the end of an arm 14 which is swung from a pivot 16 in the machine frame above the pivot 6 of the needle segment. The back gauge 10 has a rearward and upward integral extension 18 in which is 15 fixed a pin 20 working in a guideway 22 formed in the rearward and upward extension of the web 8. This guideway is so contrived with respect to the radius and pivot of the arm 14 carrying the back gauge as to 20 act as a cam path causing the engaging end of the back gauge to perform as if it were swung about the center of rotation of the needle segment, and to follow exactly the path of movement of the needle. Through 25 this arrangement, the relationship between the back gauge and the needle remains the same throughout the entire stitching operation, the prongs of the back gauge encountering the upper at exactly the level of the needle at 30 each successive stitch regardless of the variation in the thickness of the work at different points in the circuit of the shoe. Since 35 there is no change in the relative level at which the impact of the back gauge falls, no 40 varying turning impulse is imparted to the shoe to disturb its manipulation by the operator.

The improved means for actuating the back gauge in its movements towards and from the shoe, and for locking it in close contact with the shoe, comprise a light spring 24 coiled around a bolt 26 fixed in the retaining plate 28 of the back rest slide and having one end extending out tangentially to engage 50 with the protruding end of the pivot pin 12 which unites the back gauge with its swinging arm 14, such light spring combining with the effects of gravity to swing said arm 14 downwardly and forwardly and bring the 55 back gauge against the shoe.

The locking means for fixing the back gauge in the exact position at which it encounters the shoe, comprise a ratchet 30 formed integrally upon the extremity of arm 60 14, and engaged by pawls 32 pivotally mount-

ed by a screw 34 upon the rearward extension of web 8, the pawls being brought into contact with the teeth of ratchet 30 by light springs 36 suitably combined with their tail portions 38. A plurality of pawls of slightly different lengths is employed in familiar manner to give locking engagement of the back gauge against the work without back lash. Means for unlocking the back gauge to permit its retraction at the proper time 70 comprise a pin 37 engaging with the tail portions 38 of the said pawls to lift them out of engagement with the ratchet 30, said pin being fixed in the end of a lever 40, pivoted at 42 upon the machine frame. This lever 75 40 is actuated through link 44 by a cam lever 46 mounted upon a stud 48 and vibrated by the engagement of its roll 50 with the disc cam 52 fixed upon the shaft 54 of the machine.

Means for retracting the back gauge subsequent to its being unlocked, to remove it from contact with the shoe during the feeding movement of the latter, comprise a ratchet 56 upon the downwardly and rearwardly facing edge of a portion 58 formed integral- 80 upon the swinging arm 14 a short distance above its lower extremity, and a plurality of pawls 60 adapted to engage therewith, said pawls being pivoted at 62 to one end of a bell crank 64 pivoted at 66 upon the machine 85 frame, suitable springs 68 being provided to press the pawls into engagement with ratchet 56. The bell crank 64 at its upper end has a sleeve 70 pivotally combined therewith as indicated at 72, and through said sleeve is 90 passed a loosely fitting pull-rod 74 to which endwise motion fore-and-aft the machine is 95 imparted periodically through the connection of its rear end at 76 with a cam lever 78, pivoted at 80 and actuated through engagement of its roll 82 with one of the usual disc cams 52.

The end of the pull-rod 74 is threaded, and equipped with a nut 84 which encounters one end of the sleeve 70 as the pull-rod is moved forwardly by its cam lever, and rocks the bell-crank 64 in a direction carrying its pawls 60 idly down over the teeth of their coacting ratchet 56. At the end of the pull-rod is a second nut 86, and between said nut and the forward end of the sleeve 70 is confined an expanding spiral spring 88, surrounding the pull-rod, and acting as a yielding medium for transmitting force imparted to said sleeve upon rearward movement of the pull-rod to actuate bell crank 64 in the direction to raise the pawls 60 while in engagement with their ratchet 56, and thus to swing the arm 14 upwardly and rearwardly 100 to retract the back gauge 10 from the shoe. This safety spring 88 provides for postponement of the retraction, if necessary, and thus prevents damage or breakage of the parts of the mechanism in the event that through wear or for other reasons the retracting ac- 105

tion starts before the locking pawls 32 shall have been disengaged from their co-acting ratchet 30.

To release the retracting pawls 60, in order 5 to permit the spring 24 to advance the back gauge into contact with the work from its retracted position, said retracting pawls have at their free ends the portions 90 adapted to be engaged by a heel 92 formed on the 10 under side of the needle guard cam lever 94. This needle guard cam lever is actuated, as the needle starts forward towards the work, in a direction causing said heel 92 to encounter the portions 90 and force the pawls 15 60 out of engagement with the ratchet 56. The back gauge, thus released, advances with the needle, striking the shoe in close proximity to and at each side of the point of impact of the needle and just an instant ahead 20 of the needle point. It arrives in time to lay the lining, in the case of a turn shoe, closely against the form of the last so that the hole in the lining formed by the entry of the needle will be in the proper alignment with the needle hole in the upper and no distortion or 25 puckering or scraping of the lining by the needle will occur.

The spring 88 performs its yielding function in another connection also. The illustrated machine is arranged, as is customary, to be turned backwardly at the end of the sewing operation to release the tension and bring the various parts to rest at the proper point to permit the removal of the shoe. The 30 timing of the various parts is necessarily such as to carry the retracting pawls 60 upwardly, during this reverse movement of the machine, before the heel 92 on the needle guide cam lever has swung upward out of 35 the way. It is necessary to keep these pawls engaged, in order to have the machine come to rest with the back gauge retracted. Through the use of the safety spring 88, the 40 gauge-retracting movement of the pull-rod 45 74 can be performed without regard to the position of the needle-guide cam lever, the pawls 60 rising until their portions 90 engage the shoulder at the lower edge of the heel 92 and being checked in their upward travel, while the spring 88 permits continued 50 movement of the pull-rod, the spring being compressed and storing up energy which serves to carry the pawls upward on their usual course and to retract the back gauge 55 from the work as soon as the needle-guide cam-lever moves its heel 92 out of their way. This latter movement occurs just as the machine comes to rest.

60 The back gauge 10 is always retracted a uniform distance from the surface of the shoe, regardless of the thickness of the work, since the pawls 60 are moved a uniform distance at each retracting action, and take hold 65 of their ratchet without lost motion at what-

ever point it may be brought to rest through contact of the back gauge with the work.

Through the novel design and combination of the parts, the improved back gauge mechanism brings the back gauge against the work 70 promptly and positively, though lightly impelled. With this lightened impact directed at the same angle and falling at the same point on the work as the stroke of the needle, and practically simultaneously therewith, the impact of the back gauge is made to blend 75 with that of the needle, with the elimination of all disturbance of the work through pounding of the back gauge and with added facility of manipulation resulting from improved support of the shoe during the stitching.

What is claimed is:

1. An inseam shoe sewing machine having, 85 in combination, a back gauge, an arm supporting said back gauge cam operated means to swing said arm toward and from the shoe, a ratchet mounted directly upon said arm, a pawl having a fixed pivot engaging with said ratchet to lock the back gauge in proximity to the shoe and means for disengaging the pawl from the ratchet. 90

2. An inseam shoe sewing machine having, 95 in combination, a curved needle, a back gauge, an arm pivotally supporting said back gauge with capacity to swing toward and from the shoe about a center eccentric to that of the needle, a guideway combined with the back gauge for causing the latter to follow the path of the needle, ratchet means 100 formed on said arm, and pawl means to lock the back gauge in proximity to the shoe and to unlock and retract it away from the shoe. 100

3. An inseam shoe sewing machine having, 105 in combination, a back gauge organization comprising a back gauge, an arm supporting said back gauge with capacity to swing toward and from the shoe, and ratchets mounted directly upon said arm, said organization being brought to rest by contact with the shoe, a pawl, having a fixed pivot, to engage one of said ratchets to lock the back gauge in contact with the shoe, a pawl to engage another ratchet, and means for actuating said last mentioned pawl to retract 110 the back gauge from the shoe. 115

4. An inseam shoe sewing machine having, 120 in combination, a curved needle, a back gauge, an arm pivotally supporting said back gauge with capacity to swing toward and from the shoe about a center eccentric to that of the needle, a guideway causing the back gauge to follow the path of the needle, ratchet teeth upon the said arm, a pawl engaging said ratchet teeth to lock the back gauge in proximity to the shoe, means acting periodically to disengage said pawl, a second pawl engaging said ratchet teeth, and means acting periodically to impart movement to said second pawl when engaged with the ratchet. 125 130

- teeth to remove the back gauge from the shoe.
5. An inseam shoe sewing machine having, in combination, a back gauge, a swinging arm carrying said back gauge toward and from the shoe, a guideway causing the back gauge to follow the path of the needle, ratchet teeth upon said arm, a pawl engaging said ratchet teeth to lock the back gauge in proximity to the shoe, means acting periodically to disengage said pawl, a second pawl engaging said ratchet teeth, and means yieldingly acting to move said pawl bodily after its engagement with the ratchet teeth to carry the back gauge away from the shoe.
15. 6. An inseam shoe sewing machine having, in combination, a back gauge, an arm supporting said back gauge with capacity to swing toward and from the work, and means for retracting the back gauge periodically 20 a fixed distance away from the surface of the work, comprising a ratchet mounted directly upon said arm, a pawl engaging said ratchet, and a cam-actuated lever imparting bodily movement to said pawl.
25. 7. An inseam shoe sewing machine having, in combination, a back gauge, a swinging arm carrying said back gauge toward and from the shoe, a ratchet upon said arm, a pawl engaging said ratchet, a cam-actuated arm moving said pawl bodily to carry the back gauge away from the shoe, and a second cam-actuated arm disengaging said pawl to let the back gauge swing toward the shoe.
35. 8. An inseam shoe sewing machine having, in combination, a back gauge, a swinging arm carrying said back gauge toward and from the shoe, a ratchet upon said arm, a pawl engaging therewith, and means yieldingly acting to move said pawl bodily in a 40 direction to carry the back gauge away from the shoe.
45. 9. An inseam shoe sewing machine having, in combination, a back gauge, a swinging arm carrying said back gauge toward and from the shoe, a ratchet upon said arm, a pawl engaging therewith, a bell-crank carrying said pawl to cause it to retract the back gauge, a sleeve upon said bell-crank, a pull-rod sliding within said sleeve, a cam-actuated 50 lever imparting endwise movement to said pull-rod, and a spring confined between the end of the pull-rod and said sleeve, through which actuation is imparted to retract the
- back gauge with capacity for postponement if necessary.
10. An inseam shoe sewing machine having, in combination, a back gauge, a swinging arm carrying said back gauge toward and from the shoe, means for locking and unlocking the back gauge in proximity to the shoe, and means for retracting the back gauge away from the shoe approximately simultaneously with the unlocking operation including a yielding connection permitting a postponement of the retraction.
11. An inseam shoe sewing machine having, in combination, a back gauge, supporting means therefor adapted to carry the back gauge toward and from the shoe, means acting upon said supporting means to lock the back gauge in proximity to the shoe, and means for unlocking and at the same time yieldingly retracting the back gauge away from the shoe.
12. A shoe sewing machine having, in combination, a back gauge, a power operated oscillating member and an actuating linkage connecting said back gauge and power operated member, comprising a one-way driving ratchet connection and a resilient means, said power operated member acting on the ratchet connection through the resilient means.
13. A shoe sewing machine having, in combination, a back gauge, a power operated oscillating member, and an actuating linkage connecting the back gauge and the power operated member, comprising a one-way driving ratchet connection and a spring arranged between the power operated member and the ratchet connection to yield upon resistance to movement of the back gauge.
14. A shoe sewing machine having, in combination, a back gauge, a power operated oscillating member and an actuating linkage connecting the back gauge and power operated member, comprising a one-way driving ratchet arranged to retract the back gauge from the shoe and to slide idly in the other direction and a resilient means positioned to yield upon resistance to retraction of the back gauge.
- In testimony whereof I have signed my name to this specification.

ERASTUS E. WINKLEY.
